(57) CLAIM

The ornamental design of wooden basket, as shown and described.

DESCRIPTION

FIG. 1 is a top perspective view of a wooden basket showing our new design;

FIG. 2 is a front elevational view thereof; the rear elevational view being identical thereto except for the absence of an overlap in the top band;

FIG. 3 is a top plan view thereof; and,

FIG. 4 is a bottom plan view thereof.
